UNITED STATES PATENT OFFICE.

RAGNAR A. W. WILNER, OF LONG ISLAND CITY, NEW YORK.

CARPET-SWEEPER ATTACHMENT.

Application filed April 17, 1922. Serial No. 553,460.

To all whom it may concern:

Be it known that I, RAGNAR A. W. WILNER, a subject of the King of Sweden, residing at Long Island City, in the county of Queens and State of New York, have invented new and useful Improvements in Carpet-Sweeper Attachments, of which the following is a specification.

This invention relates to floor cleaning devices and has for its object the provision of a novel suction device for use in connection with and mounted upon a carpet sweeper whereby to apply suction to the rug or carpet treated for the purpose of extracting the dust in a manner similar to the action of a vacuum cleaner.

An important object is the provision of an attachment of this character which may be quickly and easily applied and which will be automatically operated by the movement of the handle toward and from the device as the sweeper is moved back and forth over a rug or carpet.

A more specific object is the provision of an attachment of this character which is mounted upon the carpet sweeper and which includes a bellows like suction device carrying a receiving bag and having control valves which automatically operate.

An additional object is the provision of a device of this character which will be simple and inexpensive in manufacture, easy to install and operate, highly efficient and durable in service and a general improvement in the art.

With the above and other objects and advantages in view, the invention consists in the details of construction to be hereinafter more fully described and claimed, and illustrated in the accompanying drawings in which:

Figure 1 is a perspective view of a carpet sweeper in action showing my device applied thereto,

Figure 2 is a plan view of my device showing the bag removed,

Figure 3 is a longitudinal section,

Figure 4 is a bottom plan view,

Figure 5 is a cross section showing the structure in collapsed position,

Figure 6 is a similar view showing the device in extended position,

Figure 7 is a detail section through the outlet valve and

Figure 8 is a detail section through the inlet valve.

Referring more particularly to the drawings the letter A designates a conventional carpet sweeper the construction of which forms no part of the present invention and which is therefore not illustrated in particular detail. Suffice it to say that this carpet sweeper is operated by means of a handle B by means of which it is pushed back and forth over the surface to be cleaned, the handle naturally swinging in an arc as the device is pushed from or pulled toward the operator.

In carrying out my invention I provide a suction device which is of bellows like formation and which includes spaced upper and lower plates 10 and 11 which are hingedly connected at one edge as shown at 12 and which are together hinged upon the carpet sweeper by means of one or more hinges 13. The numeral 14 designates a flexible covering such as leather or the like which is secured to the edges of the plate members 10 and 11 to constitute the bellows.

Extending downwardly from the lower plate 11 is an inlet tube 15 which communicates with a hole 16 in the bottom plate and which carries a floor engaging suction nozzle 17 which must necessarily be of hollow formation and formed with a longitudinal slot 18, the construction being similar to that of the inlet nozzle of the vacuum cleaner.

Mounted upon the top of the upper plate 10 is a tube 19 which communicates with a hole 20 and which extends into a cylindrical casing 21 which is provided with perforations 22 permitting the passage of air. Secured to and surrounding this casing 21 is a bag 23 of the material commonly used in vacuum cleaners, that is: a material which will readily permit passage of air but prevent passage of dust therethrough.

Internally of the bellows the bottom plate 11 carries a flap valve 24 which closes the hole 16 when the bellows is collapsed. Upon the top of the plate 10 is mounted a similar flap valve 25 which is adapted to open when the bellows is collapsed for establishing communication between the interior of the bellows and the tube 19, it being of course readily apparent that the tube 19 must be enlarged where it connects with the plate 10 so as to enclose the flap valve. Located within the bellows is a spring 26 which operates to hold the plates 10 and 11 apart or in expanded position.

In the operation it will be seen that under the influence of the spring 26 the bellows will be in expanded position with its top plate 10 engaging the handle B of the carpet sweeper. When the sweeper is moved back and forth in the usual manner it will be apparent that the handle B will swing in an arc with respect to the surface traveled over so that the bellows will be alternately collapsed and subsequently expanded. When the collapsing occurs it will be apparent that any air within the bellows will be discharged into the tube 19 and casing 21 into the bag, the air issuing from the latter and the dust being retained therein, the flap valve 24 being at this time closed. When the pressure of the handle against the bellows ceases, the spring 26 will expand the bellows whereupon the valve 25 will close and the valve 24 will open to suck air and dust through the nozzle 17 into the bellows. This cycle of operations continues as long as the carpet sweeper is in use.

From the foregoing description and a study of the drawings it will be apparent that I have thus provided a very simply constructed and easily applied vacuum cleaning attachment for carpet sweepers which will be automatic in operation and which requires no power in addition to the manual labor involved in pushing the carpet sweeper back and forth over the surface to be cleaned. In this way it will be seen that the device should be very effective and in fact more so than most of the common vacuum cleaners as it is well known that carpet sweepers are provided with rotary

brushes which pick up the nap while loosening any accumulation of dust. Owing to the simplicity of construction and the fewness of the parts it is apparent that there is nothing to get out of order and that the device should have a long life.

While I have shown and described the preferred embodiment of the invention, it is of course to be understood that I reserve the right to make such changes in the form, construction and arrangement of parts as will not depart from the spirit of the invention or the scope of the subjoined claim.

Having thus described my invention I claim:

A vacuum cleaner attachment for sweepers consisting of a bellows having a movable leaf carrying a hinge adapted to be secured upon the top of a conventional carpet sweeper, a spring normally tending to expand the bellows, the movable leaf of the bellows being designed for engagement by the pivoted handle of the carpet sweeper during movement of the sweeper whereby to compress the bellows, an inlet nozzle of elongated formation designed to engage the floor at one edge of the carpet sweeper, a pipe supporting said nozzle and leading into the bottom of the bellows, a flap valve at the entrance of said pipe into the bellows, an outlet pipe on the movable leaf of the bellows, a flap valve controlling passage of air into said outlet pipe, and a perforated housing surrounding said outlet pipe and designed to support a dust collector.

In testimony whereof I affix my signature.

RAGNAR A. W. WILNER.
